UNITED STATES PATENT OFFICE.

FRANK B. FELTON, OF BRIDGEPORT, CONNECTICUT.

DESIGN FOR A BICYCLE-SUPPORT.

SPECIFICATION forming part of Design No. 27,632, dated September 7, 1897.

Application filed June 15, 1896. Serial No. 595,692. Term of patent 3½ years.

To all whom it may concern:

Be it known that I, FRANK B. FELTON, a citizen of the United States, residing at Bridgeport, in the county of Fairfield and State of Connecticut, have invented and produced a new and original Design for a Bicycle-Support; and I do declare the following to be a full, clear, and exact description of the same, reference being had to the accompanying drawing, forming a part thereof.

The leading feature of my design resides in the shape of the angularly-disposed legs, one of which legs is deflected at F, thence extending vertically at G, thence angularly at H, and terminating in the horizontal foot J. The upper portion of such leg has the short vertical part D to rest against the vertical

portion A' of the opposite leg. This vertical portion A' extends into the angular portion A and the horizontal foot K. The upper portion of the part A' is continued upward and rearward to form the upper curved back C C' and curved portion or seat B B', the extreme free end B² projecting forward to the vertical part A', but to one side thereof. 20 25

What I claim is—

The design for a bicycle-support; substantially as herein shown and described.

In testimony whereof I affix my signature in presence of two witnesses.

FRANK B. FELTON.
